UNITED STATES PATENT OFFICE.

HAROUTIUN K. KOUYOUNJIAN, OF CLEVELAND, OHIO.

DESIGN FOR A GENERATOR AND RADIATOR COOLING FAN FOR MOTOR-VEHICLES.

47,079.

Specification for Design.

Patented Mar. 9, 1915.

Application filed December 18, 1913. Serial No. 807,560. Term of patent 7 years.

To all whom it may concern:

Be it known that I, HAROUTIUN K. KOUYOUNJIAN, a subject of the Sultan of Turkey, residing at Cleveland, in the county of Cuyahoga and State of Ohio, have invented a new, original, and ornamental Design for a Generator and Radiator Cooling Fan for Motor-Vehicles, of which the following is a specification, reference being had to the accompanying drawings, forming part thereof.

Figure 1 is a side elevation and Fig. 2 is

an end elevation of a generator and radiator cooling fan for motor vehicles, showing my new design.

I claim:

The ornamental design for a generator and radiator cooling fan for motor vehicles, substantially as shown.

HAROUTIUN K. KOUYOUNJIAN.

Witnesses:

L. I. PORTER,
A. J. HUDSON.
